UNITED STATES PATENT OFFICE.

CHARLES B. MOORE, OF EVANSTON, ILLINOIS, ASSIGNOR TO AMERICAN ARCH COMPANY, OF NEW YORK, N. Y., A CORPORATION OF NEW YORK.

LOCOMOTIVE-BOILER FURNACE.

1,115,955.

Specification of Letters Patent.

Patented Nov. 3, 1914.

Application filed December 18, 1911. Serial No. 666,353.

To all whom it may concern:

Be it known that I, CHARLES B. MOORE, a citizen of the United States, and a resident of the city of Evanston, Cook county, Illinois, have invented certain new and useful Improvements in Locomotive-Boiler Furnaces, of which the following is a specification.

My invention relates to improvements in locomotive furnaces and has particular reference to improvements in refractory baffles or deflecting walls commonly called arches for the fireboxes of locomotives.

The general objects of my invention are to provide a refractory arch which can be easily and quickly installed in a locomotive firebox; to provide an arch which shall be of light weight and low cost; to provide an arch which shall be easy to repair, and parts of which may be readily removed for the purpose of affording easy access to the side sheets and flue sheet of the firebox; and to provide an arch of a form that shall materially assist in the admixing of the firebox gases and the igniting of the gases and the fuel particles carried thereby.

A special object of my invention is to provide an improved refractory arch construction having the characteristics herein outlined which shall be particularly adapted for installation and use in locomotive boiler fireboxes that are equipped with a plurality of circulating or arch supporting tubes.

My invention consists in the several improvements, the various constructions and the combinations of parts by which the above objects are attained, together with others hereinafter appearing, and all as herein fully described and particularly pointed out in the appended claims.

My invention will be more readily understood by reference to the accompanying drawings, forming a part of this specification, and in which:

Figure 1 is a vertical, central, longitudinal section of a locomotive firebox equipped with a refractory arch embodying my invention; Fig. 2 is a horizontal sectional view of the firebox on line 2—2 of Fig. 1; Fig. 3 is a transverse vertical sectional view of the firebox on the line 3—3 of Fig. 1; Fig. 4 is a transverse vertical fragmentary sectional view of the firebox and arch on the line 4—4 of Fig. 1; Fig. 5 is a fragmentary perspective view of one of the arch bricks; Fig. 6

is a perspective view of one of the arch spacing or key bricks; Fig. 7 is an enlarged fragmentary transverse section of the arch on the line 7—7 of Fig. 2; and Fig. 8 is a perspective view of one of the side arch key 60 bricks.

My invention is capable of embodiment in arches occupying various positions in the firebox and having different specific functions. I have, however, confined the illustration of the invention to so-called front arches, but I wish it understood that my invention is not limited to this specific form or position of arch. A so-called front arch usually occupies an inclined position in the 70 firebox extending substantially from side to side therein and having its forward end in substantial abutment with the flue sheet. The principal function of these arches is to deflect the firebox gases out of their direct 75 line of flow from the grate to the flues and cause them to travel back and forth in the firebox thereby not only distributing their heat to substantially the whole interior surface of the firebox and especially throughout 80 the length of the crown sheet, but also serving to admix or commingle the various strata of gases and thereby assist in the complete combustion of the fuel. A second result accomplished by the deflection of the 85 gases is that they are retained thereby in the firebox long enough to accomplish their complete combustion before they escape through the flues. Front arches constructed in accordance with my invention not only perform the functions above mentioned, but also by reason of their comparative thinness 90 soon attain the maximum temperature of the firebox gases and thereby assist in the ignition of the gases and fuel particles carried 95 thereby.

A locomotive firebox, as illustrated in the drawings, is made up of a flue sheet 2, side sheets 3—3, a crown sheet 4 and a rear sheet 5. The firebox has a grate 6, and the rear 100 sheet is provided with a fuel door 7. Flues 8 lead forward from the flue sheet.

The firebox, illustrated, is equipped with four arch or circulating tubes 9, the same extending from the lower portion of the flue 105 sheet to the upper portion of the rear sheet and serving to increase the circulation of water between the front and rear water legs of the firebox.

A principal feature of my invention re- 110

sides in an arch which is made up or built of a plurality of substantially identical refractory bricks which are so formed that adjacent bricks may be relatively reversed in position and also that when placed in position on the tubes they will be locked together in such a manner that the arch as a whole will have the permanent features of a solid arch, while at the same time it will be flexible to a certain degree. I build my arches of bricks which are long enough to rest upon two adjacent tubes, the size of the bricks otherwise than their length being determined by the features that they shall be as large as possible while not too heavy to be easily handled and that they shall be small enough to be readily passed through the fire door of the firebox.

In the form of arch construction illustrated, I make use of the interlocking brick members A, as I have stated, and I make these bricks long enough to rest upon two adjacent tubes. I make these bricks thick enough to have sufficient strength to carry their own weight, and I preferably provide their upper and lower surfaces with shallow pockets or depressions which not only reduce their weight, but also provide the arch with many subsidiary gas-mixing pockets and 30 walls or baffles. I arrange these bricks in substantially a single plane resting upon the tubes and hold them transversely in the firebox by means of interlocking wedge bricks B which I interpose between the ends 35 of the transverse rows of arch bricks and the side sheets 3 of the firebox. I form the principal portion of the arch, or the arch proper, of a series of the rows of interlocking arch brick and this main portion of the arch extends transversely in the firebox substantially equal with the lateral extent of the arch supporting tubes and I retain it 40 transversely in the firebox upon the tubes by means of the interlocking wedging key bricks B arranged between this main portion of the arch and the side sheets 3, as stated.

All of the arch bricks A are substantially identical in shape, a peculiar feature being 50 that their opposite ends are cut away in such a manner that they are provided on each end with a projecting ledge or tongue A¹. These tongues extend across the width of the brick and are so formed that when the bricks are arranged in a row end to end they interlock the adjacent bricks together in such a manner that they retain the bricks of the row in position transversely of the firebox. As shown in the drawings, these 55 tongues A¹ are substantially half the thickness of the body of the brick, which provides the brick with complementary grooves or cut-away portions A² of a depth equal to the depth of the tongue A¹ and consequently the 60 overlapping ends of two adjacent bricks

provides a thickness of the arch at this point substantially equal with the thickness of other portions of the arch. Each of these projecting tongues A¹ is provided with a smaller projection A³ at its middle portion, 70 and immediately inside this smaller projection A³ the tongue is provided with a complementary socket or depression A⁴ adapted to receive the complementary projection A³ of the adjacent brick. These complementary 75 projections or hooks A³ serve to hook the adjacent bricks of the row together and prevent the separation of the adjacent bricks. Another resultant feature of the complementary projections A³ is that they interlock the bricks against transverse movement and also against relative movement longitudinally on the supporting tubes. Furthermore, the extreme end surfaces A⁵ of the tongues A¹ abut the complementary shoulder A⁶ of the adjacent brick and the individual bricks of the row thereby mutually retain each other in position. Each of these bricks is provided upon the side face, the extension of which forms the tongues A¹, 80 with a large depression or gas-mixing pocket A⁷ which is nearly the full extent of the brick in size. This pocket not only serves to reduce the weight of the brick without decreasing its strength to any appreciable extent but also provides the brick with relatively thin marginal edges or ledges A⁸. These pockets and ledges provide the individual bricks with subsidiary gas-deflecting 85 walls or surfaces and consequently add materially to the gas mixing effect of the arch, and being thin they soon attain the maximum temperature of the firebox and thereafter serve to ignite the gases of combustion and the fuel particles carried thereby. I 90 provide the opposite face of the bricks with oppositely arranged smaller gas mixing pockets A⁹, the brick having a central transverse wall A¹⁰ separating these pockets from each other. These pockets extend to the end 95 of the brick and are nearly the full width of the brick leaving marginal edges A¹¹ similar to the marginal edges A⁸ on the other side of the brick. The ends of these marginal edges A¹¹ form the shoulders A⁶ 100 on this side of the brick before spoken of.

The arch locking bricks B are substantially identical in form, and they are narrower than the main or arch bricks A. They are arranged in upwardly and outwardly inclined positions at each side of the arch, resting at their inner ends upon the projecting tongues A¹ of the arch bricks and leaning against the side sheets of the firebox at their upper and outer ends. 105 They are of a length to be wedgily interposed between the main part of the arch and the side sheets of the firebox and thereby lock or key the arch in position transversely in the firebox. Each of the bricks 110

B is tapered longitudinally and their larger ends 'B' which are placed upon the outer ends of the bricks A are provided with vertically projecting tongues B² and adjacent 5 sockets B³ of dimensions to mutually interlock with the projection A³ and the sockets A⁴ of the arch bricks A. The projection or tongue B² is centrally formed and consequently when a brick B is placed in position 10 between each of the bricks A in the side row and the adjacent side sheet the bricks B are separated from each other or spaced apart and in such position the interlocking engagement of the bricks A and B retains 15 the bricks B in position longitudinally of the firebox. In other words, the bricks being thus interlocked are thereby prevented from sliding down toward the flue sheet and are securely held in their proper position 20 where they serve to interlock the individual rows of arch bricks against transverse movement in the firebox. The bricks B, as already stated, are tapered, and their outer ends are made both thinner and narrower 25 than their inner ends making it relatively an easy matter to trim these bricks to properly wedgingly fit between the ends of the transverse rows of arch bricks and the side sheets of the firebox. For the purpose of 30 more clearly illustrating this structure I have omitted one of the bricks B from Fig. 2 indicating its position by dotted lines.

As clearly illustrated in Figs. 1, 2 and 3, I prefer to space the lower end of the arch 35 away from the flue sheet, but of course it will be understood that the functions of the arch itself would not be materially changed by placing the lower row or tier of bricks against the flue sheet. To space the arch 40 away from the flue sheet, I make use of spacing bricks C of the same general form as the wedge-shaped locking bricks B. I place one of these bricks upon the lower end of each of the arch supporting tubes 9 with 45 its smaller end in contact with the flue sheet, and each of these bricks is provided on its lower surface with a longitudinal groove C¹ which substantially fits the upper surface of the tube upon which it rests and the brick 50 thereby rests securely in position, particularly when the arch is built as the weight of the arch rests against these bricks and firmly retains them on the tubes. Each of these bricks is provided on its larger end on 55 the grooved or underside with a transverse ledge or projecting shoulder C² which is divided into two parts by the groove C¹. These ledges, when the bricks are laid on the tubes, as heretofore explained, extend 60 rearwardly under the lower edge of the arch bricks A and serve to more securely hold said bricks C in place.

In building the arch, as illustrated in the drawings, wherein a firebox provided with 65 four of the inclined circulating tubes is

shown, I place one of the bricks A upon the lower ends of the two adjacent outer tubes 9 at each side of the firebox with their projecting tongues A' laid flat upon the tubes; then I place a middle brick reversed in position upon the two with its projecting tongues A' resting upon the tongues of the bricks already in position and the projections A³ of the various bricks entering the complementary sockets A⁴ of adjacent 70 bricks. These three bricks are therefore interlocked against relative movement both transversely and longitudinally in the firebox. I then place one of the locking bricks B at each end of the row thus formed 75 which locking bricks wedge the row of arch bricks in position and prevent its bodily movement transversely in the firebox. The bricks B are moreover interlocked with the row of arch bricks both as to relative longitudinal and transverse movement in the firebox. The arch is completed by similar transverse rows of the arch bricks and the locking bricks laid upon the inclined tubes above the first row. The arch as a whole 80 usually comprises a sufficient number of these transverse rows of arch bricks to bring the upper edge of the arch body to about the center of the firebox, which thereby provides the firebox with an inclined firebrick 85 deflecting wall arranged between the grate and the flues and provided on its under surface with a plurality of subsidiary gas-mixing and deflecting walls.

It will now be seen that the arch as described 100 comprises several longitudinal rows of bricks, the alternate rows being reversed in position, some of the rows resting at their edges upon the tube and the reversed rows resting upon, interlocked with and supported by the first rows.

As many modifications of my invention will readily suggest themselves to one skilled in the art, I do not limit or confine my invention to the specific structure shown 110 herein and described.

Having thus fully described my invention, I claim as new and desire to secure by Letters Patent:

1. A locomotive boiler firebox having a 115 plurality of arch supporting tubes, in combination with a refractory front arch therein resting on said tubes, said arch comprising a plurality of individual refractory arch bricks laid upon and supported by said 120 tubes, and locking bricks interposed between the edges of said arch body and adjacent side sheets of the firebox resting at their inner ends upon said arch body, the arch body and said bricks being formed with 125 mutually interlocking projections and sockets and said locking bricks being thereby retained against movement relatively to the arch body.

2. A locomotive boiler firebox having a 130

- plurality of transversely spaced inclined arch supporting tubes, in combination with a refractory front arch comprising several transverse rows of arch bricks arranged side by side resting upon and supported by said tubes, and a wedging or locking brick arranged at each end of each of said rows of bricks resting thereon and leaning against the adjacent side sheet, said locking bricks being narrower than the arch bricks and said arch and locking bricks having mutually overlapping and interlocking ends whereby the locking bricks are retained against movement relatively to the arch bricks.
3. A locomotive boiler firebox having a group of inclined arch tubes, a transverse row of slab-like fire bricks resting upon the inclined portions of said tubes and laterally co-extensive with said group of tubes, in combination with marginal bricks resting at their inner ends upon the ends of said transverse rows of arch bricks and leaning against the side sheets, said transverse rows of bricks and marginal bricks having substantially identical mutually interlocking projections and sockets whereby said marginal bricks are held against longitudinal movement in the firebox relatively to the transverse rows of fire bricks.
4. A locomotive boiler firebox having a plurality of inclined water-circulating tubes therein, in combination with a refractory front arch resting on said tubes and against the flue sheet, said arch comprising a plurality of substantially identical transverse rows of fire bricks laid side by side, each brick having half thickness flanges extending from its ends adapted to overlap a similar flange on the next adjacent brick, the alternate bricks of each row being reversed in position and all of said bricks having substantially identical vertical inter-

locking projections and complementary sockets whereby the bricks are retained against longitudinal separation, and a marginal brick of less width than the fire bricks arranged at each end of each row thereof, said marginal bricks being interposed between the fire bricks and the adjacent side sheet of the firebox and formed with a complementary projection and socket substantially identical with the projections and sockets of the fire bricks and adapted to engage therewith.

5. A locomotive boiler firebox having a plurality of inclined water-circulating tubes therein, in combination with an inclined refractory front arch therein and thereon abutting the flue sheet and comprising a plurality of slab-like bricks resting upon and supported by said tubes, said arch being laterally co-extensive with said tubes and the edge portions having vertically extending projections and complementary sockets, and a row of marginal bricks arranged at each side of said arch resting at their inner ends upon the edges of the arch and leaning against the adjacent respective side sheets, the individual bricks of said rows being separated from each other and each having projections and sockets similar to the projections and sockets on the edges of the arch and adapted to interlock therewith whereby the marginal bricks are held against movement relatively to the arch.

In testimony whereof I have hereunto set my hand this 5th day of December, 1911, in the presence of two subscribing witnesses.

CHARLES B. MOORE.
